FIG. 1 is a front perspective view of an embodiment of an end effector or end of arm tool made in accordance with the subject design.

FIG. 2 is a back perspective view thereof.

FIG. 3 is a front view thereof.

FIG. 4 is a back view thereof.

FIG. 5 is a left side view thereof.

FIG. 6 is a right side view thereof.

FIG. 7 is a top view thereof.

FIG. 8 is a bottom view thereof.

FIG. 9 is a front perspective view of an interfacing end of the end effector or end of arm tool of FIGS. 1-8 in isolation.

FIG. 10 is a rear perspective view thereof.

FIG. 11 is a front view thereof.

FIG. 12 is a rear view thereof.

FIG. 13 is a left side view thereof.

FIG. 14 is a right side view thereof.

FIG. 15 is a top view thereof; and,

FIG. 16 is a bottom view thereof.

The broken lines illustrate portions of the article and form no part of the claimed design.

1 Claim, 16 Drawing Sheets
